ABSTRACT: This disclosure relates to improvements in multi-ply bags which generally include at least an outer wrapper and an inner liner, and is particularly directed to a bottom construction formed by adhesively securing together a plurality of closure panels or flaps. The securing is effected by forming heat-shrunk openings in the inner liner to expose the interior of the outer wrapper which is brought into overlying adhesive contact with the exterior of another closure flap or panel such that the bond is between the material of the outer wrapper.

MULTI-PLY BAGS

The most simple conventionally fabricated multi-ply bag is a two-ply construction having an inner liner and an outer wrapper. Such a bag is customarily fabricated from two separate but continuous webs which are laminated, spot pasted, or otherwise secured to each other. In bags of this type it is known to form the liner web from grease resistant, moistureproof material while the web forming the wrapper is generally constructed from heavy gauge paper stock material to provide the requisite bag strength. One such conventional bag is disclosed in commonly assigned U.S. Pat. No. 3,289,915, issued Dec. 6, 1966, in the name of Anthony J. Civitello.

In the latter-noted patent, reference is made to the difficulty in forming commercially acceptable bag bottoms because of the difficulty of adhesively securing the inner liner of one flap or closure to an outer surface of the wrapper and another flap or closure to form the final closure of the bag bottom. This is because the inner liner is either constructed from or coated with polyethylene or other relatively impermeable material, and the water of conventionally employed water-based adhesives is not absorbed by the liner thus precluding the formation of a strong seal between the liner and that portion of the wrapper to which the liner flap is overlaid. In addition, the impermeable and generally nonwettable nature of such liners or coatings thereon results in excessive setting up time, thereby increasing the cost for the manufacture of such bags.

One solution to this problem is provided in the latter-noted patent by severing a portion of the liner of an outer closure flap and folding the severed portion upon itself to expose the inner surface of the outer wrapper of the outer closure flap to an outer surface of an adjacent inner closure flap whereupon adhesive applied to these surfaces provides an efficient and strong bottom construction by effecting an adhesive bonding between only uncoated paper surface portions of the inner and outer wrapper closure flaps. However, this construction can only be practiced when the liner and the wrapper webs are drawn from separate rolls such that the liner web may be severed and the portion folded prior to the webs being laminated to each other.

In keeping with the present invention a multi-ply bag is constructed from either two separate webs each drawn from a separate roll, or a single laminated web drawn from a single roll. In either case the web which eventually forms the inner liner is constructed from heat-shrinkable synthetic polymeric or copolymeric material, such as polyolefin, polyethylene, polypropylene, pliofilm, etc. The liner material may be nonoriented or oriented, although in the practice of the invention oriented material has been found more desirable. During the feeding of the individual or laminated webs heating means of any type are applied directly against or close to portions of the inner web which eventually form the inner surface of the outermost closure panel or flap such that the heat causes thermal degradation of the liner material resulting in its shrinking to form one or more openings. This may be accomplished by, for example, positioning any type of conventional heating elements upon a rockable shaft disposed transverse to the path of movement of the liner web. The shaft may then be rocked in timed relationship to the movement of the liner web, by means such as disclosed in the latter-noted patent, to bring the heating elements contiguous to or in direct contact with the liner material whereupon the heat thermally degrades the inner liner tube at one or more points in the eventual outermost closure flap area to form the openings heretofore noted whereupon adhesive thereafter applied to the webs results in the bonding of the inner surface of the outermost closure flap of the wrapper to adjacent exterior surfaces of the wrapper material.

It is, therefore, a primary object of this invention to provide an improved multi-ply bag formed of separate or laminated liner and wrapper webs wherein the improvement comprises

means defining heat-shrunk openings formed in a portion of the liner web of an outermost closure flap, and adhesive means bonding the interior surface of the outermost closure wrapper to an exterior surface of an adjacent flap through the heat-shrunk openings.

A further object of this invention is to provide a novel multi-ply bag bottom construction wherein the openings are defined by edges of thermal degradation, and the material of the inner liner is constructed from heat-shrinkable synthetic polymeric material.

A further object of this invention is to provide a novel multi-ply bag bottom construction of the type heretofore defined wherein the material of the inner liner is preferably oriented polymeric material and may be, for example, polyethylene, polypropylene, polyolefin, etc.

With the above and other objects in view that will hereinafter appear, the nature of the invention will be more clearly understood by reference to the following detailed description, the appended claimed subject matter, and the several views illustrated in the accompanying drawing.

IN THE DRAWING

FIG. 1 is a perspective view of a multi-ply bag constructed in accordance with this invention, and illustrates the bottom construction thereof prior to folding an outermost closure flap to its final position, as shown in FIG. 4.

FIG. 2 is a fragmentary enlarged elevational view of the bottom construction of the bag of FIG. 1, and illustrates the inner surface of the outer wrapper of the outermost closure flap exposed through heat-shrunk openings of the inner liner.

FIG. 3 is an enlarged fragmentary sectional view taken generally along line 3-3 of FIG. 2, and more clearly illustrates the openings of the inner liner and the manner in which the inner surface of the outer wrapper is exposed therethrough.

FIG. 4 is a fragmentary side elevational view of the bag bottom construction, and illustrates the outermost closure panel adhesively secured to underlying exterior surfaces of the wrapper through the heat-shrunk openings.

A novel multi-ply bag constructed in accordance with this invention is generally designated by the reference numeral 10 and includes a bottom construction 11 which, insofar as the formation and folding thereof is concerned, is a conventional square bottom. Although the invention is described in conjunction with a square bottom bag, it is to be understood that satchel or any other conventional bottom construction may be employed so long as at least one closure panel is brought into overlying adhesive contact with another closure panel to form the bag bottom. Furthermore, though the bag 10 will be described hereinafter as being formed of only two plies, tubes or webs, it is to be understood that the invention can be carried out with any reasonable number of thicknesses or plies. In addition, though reference is made to an outer wrapper and an inner liner, the invention is likewise applicable to coatings, as opposed to webs, of heat-shrinkable material applied to an outer wrapper, or an outer wrapper and an inner liner of which the latter is likewise provided with a coating of heat-shrinkable material. The essence of the invention is the provision of any type of multi-ply bag-stock material in which at least one ply, coating, web, or like laminate is constructed from heat-shrinkable material and is subjected to thermal degradation to form openings through which an adhesive bond may be formed to readily cross-bondable material.

The multi-ply bag 10 includes bellows 12, 13 formed by folding along fold lines 14 through 16 and 18 through 20, respectively. The bellows or gussets 12, 13 may, of course, be eliminated if desired.

The bag 10 is constructed from an outer wrapper 21 and an inner liner 22. The outer wrapper 21 is preferably constructed from paper stock material, and prior to being folded as shown in FIG. 1, is of a generally rectangular configuration, in the manner disclosed in the latter-identified patent.

The entire inner surface of the wrapper 21 is covered by the liner 22, and the latter may be in the form of a separate web spot pasted or laminated to the interior surface of the wrapper 21. In lieu of the liner 22 being formed of a separate web, the same may merely be a coating applied upon the interior surface of the web from which the outer wrapper 21 is constructed. In any event, the liner 22 is constructed from heat-shrinkable synthetic polymeric or copolymeric material, such as polyolefin, polypropylene, polyethylene, pliofilm, and is preferably but not necessarily oriented polymeric or copolymeric material.

The square bottom 11 is folded in the manner described more fully in the latter-noted patent and known in the prior art by first inwardly folding a pair of side flaps or closure panels 24, 25, along respective fold lines 26, 27. An inner closure panel or flap 28 is next folded along a fold line 30 into partial overlying relationship to the side panels or flaps 24, 25. In both FIGS. 1 and 2, the exterior surface of the outer wrapper of the panels or flaps 24, 25, and 28 is exposed.

As best shown in FIGS. 1, 2, and 3, the bag bottom 11 includes an outermost closure panel or flap 32 formed by the material of both the outer wrapper 21 and the inner liner 22. The stippling in FIG. 2 indicates innermost surfaces of the outer wrapper exposed through opening, generally designated by reference numeral 33, formed in the material of the inner liner 22. The openings 33 are formed by subjecting the liner material to heat sufficient to cause thermal degradation thereof whereupon, due to the heat-shrinkable nature of the inner liner material, the openings 33 are formed. Edges 34 of each of the openings 33 are irregular, rough, and by visual appearance can be seen to have been formed by the thermal degradation of the material of the liner 22.

Prior to folding the outermost closure flap or panel 32 along a fold line 35 to complete the formation of the bag bottom construction 11, adhesive is applied upon the liner 22 of the outer closure flap 32 and thereby contacts the stipled inner surface of the outer wrapper. When overfolded to the position

shown in FIG. 4, adhesive thereby bonds the inner surface of the outer wrapper of the outer closure flap 32 to the exterior surfaces of the flaps or closures 24, 25, and 28. Because of the openings 33, it is immaterial that the adhesive upon the impermeable liner 22 in the area of the closure 32 is not absorbed thereby because the adhesive will be absorbed by the exterior porous surface of the closure panels 24, 25, 28, and the interior surface of the outer wrapper of the closure 32, thereby achieving an excellent adhesive bond.

While preferred forms and arrangements of parts have been shown in illustrating the invention, it is to be clearly understood that various changes in details and arrangement of parts may be made without departing from the spirit and scope of this disclosure.

I claim:

1. In a multi-ply bag bottom construction of the type including at least an inner liner tube and an outer wrapper tube, and fold line means for defining a flap foldable into exterior overlying relationship to an adjacent exterior portion of the outer wrapper tube, the improvement comprising means defining heat-shrunk thermal-degraded edges of openings formed in a portion of said inner liner tube at said flap, and means securing said exterior portion to a portion of said outer wrapper tube at said flap through said openings.

2. The multi-ply bag bottom construction as defined in claim 1 wherein said securing means is an adhesive bond.

3. The multi-ply bag bottom construction as defined in claim 1 wherein said inner liner tube is constructed from heat-shrinkable synthetic polymeric material.

4. The multi-ply bag bottom construction as defined in claim 1 wherein said inner liner tube is constructed from heat-shrinkable synthetic oriented polymeric material such as polyolefin, polyethylene, polypropylene, pliofilm, etc.

5. The multi-ply bag bottom construction as defined in claim 2 wherein said inner liner tube is constructed from heat-shrinkable synthetic polymeric material.
